[57] CLAIM

The ornamental design for a food serving cart, as shown
and described.

DESCRIPTION

FIG. 1 is a top perspective view of a food serving cart
showing my new design, a tray of the food serving cart
being removed for clarity of illustration;

FIG. 2 is a vertical sectional view thereof; and

FIG. 3 is a sectional top view thereof taken along the
line 3—3 of FIG. 2.

FIG. 1

FIG. 2FIG. 3
